(57) CLAIM

The ornamental design for a golf club support, as shown and described.

DESCRIPTION

FIG. 1 is a top perspective view of a golf club support;

FIG. 2 is a front elevational view thereof;

FIG. 3 is a right elevational view thereof;

FIG. 4 is a rear elevational view thereof;

FIG. 5 is a left elevational view thereof;

FIG. 6 is a top plan view thereof;

FIG. 7 is a bottom plan view thereof; and,

FIG. 8 is a perspective view showing the golf club support in an exemplary use.

The elements shown in broken lines in FIG. 8 depict environmental structures and form no part of the claimed design.
